UNITED STATES PATENT OFFICE.

GEORG SPIESS, OF LEIPZIG CONNEWITZ, GERMANY.

SHEET-FEEDING APPARATUS.

967,077.

Specification of Letters Patent. Patented Aug. 9, 1910.

Application filed April 2, 1909. Serial No. 487,470.

To all whom it may concern:

Be it known that I, GEORG SPIESS, subject of the Emperor of Germany, residing at Leipzig Connewitz, Germany, have invented 5 new and useful Improvements in Sheet-Feeding Apparatus, of which the following is a specification.

In those devices in which by mechanical means one sheet after the other must be 10 taken from a supply and led to the delivery the transfer of the sheet occurs by means of a friction wheel. This is a rubbing wheel continuously rotating which sinks to the sheet for the purpose of transporting and 15 during the rest of the time must be lifted from the sheet. The putting into action of the friction wheel is to be effected by the sheet itself and in case of delicate paper care must be taken that in spite of the weakness 20 of the paper this transfer of motion is possible. It is customary for the transfer of this movement to employ a feeler arm which enters a depression in the transfer roller over which the sheet must be carried along. 25 In such arrangement the feeler arm is lifted and the release which is intended to lift the friction arm is thereby brought into action. The release arrangements which are in use 30 for this purpose are of very involved nature and difficult to apply and regulate so that they can be supervised only by very skilful workmen. This deficiency is to be removed according to this invention by means of a 35 freeing device for the friction wheel having inclined faces and arrested by a locking device which serves as a carrier for the sheet feeler.

This invention is set forth in the following specification and claim and illustrated 40 in the annexed drawing in which:

Figure 1 is a sectional side elevation of a device or sheet feeder embodying this invention. Fig. 2 is a plan view of the freeing device.

45 The friction wheel A is journaled in a bell crank lever B which can be moved by a second bell crank lever C. By means of spring D and said levers B and C the friction wheel A is pressed down onto the table.

50 The freeing device which is intended to momentarily lift the friction wheel consists according to this invention of a freeing device F with an inclined face E. The freeing device is intended to engage the bell crank lever C and which is retarded in its action 55 by a locking device or arm G which at the

same time serves as a carrier for the sheet feeler H. In the example shown in the drawing the freeing device F is mounted for vertical movement in a vertical channel in 60 the cross-carrier W and a spring X connected to its upper end tends to normally draw it upward. The freeing device F is, however, held in its lowermost position by the locking arm G. The locking arm G is pivotally suspended and provided with a nose I which butts against the inclined recess of 65 the freeing device F. On a releasing stroke of the locking device its nose I will slide over the inclined surface E of the freeing 70 device F and will be forced by the latter to make a determined swing. The locking arm G or the shaft K thereof also serves as a carrier for the sheet feeler jointed thereto. In the position of rest shown the sheet feeler 75 enters a cut out in the transfer roller L. The sheet feeler H is caused to make a stroke or swing as soon as a sheet is led to the transfer roller L. The edge of the contacting sheet gives a swing to the feeler arm. 80 Hereby it is to be brought within reach of a movable part of the machine and to receive a movement which must be transferred to the locking device G. A slight movement 85 of the latter however also causes the release of the freeing device F which rises under the spring action and at the same time by means of its inclined face E effects a full swing of the locking arm of sufficient extent to lift the feeler H above the plane of 90 the path of the sheet so that the sheet feed can take place without hindrance.

In the example shown a spring actuated tappet M is brought under the action of a rotating tappet wheel N which is shown only 95 for part of its circumference as provided with teeth. By the turning of this wheel the tappet M receives from such teeth rapidly succeeding small impacts. If now the feeler arm is lifted so far by the advancing 100 sheet that its rear end O comes into the path of the tappet M the blow of the same will cause the locking device to make a small swing which then causes the release of the freeing device F. The latter rises under spring action and carries the bell crank levers B and C as also the friction wheel A 105 into elevated position, that is the friction wheel is put out of action.

To hold the wheel in the release position 110 until a new sheet is to be advanced an arm P is jointed to the freeing device F and when

lifted engages under the projection Q of bell crank lever C. This must also occur in case the friction wheel A has not advanced any sheet and the release arrangement has not 5 come into action.

For lifting the arm P there is provided a curved disk S on the shaft R which makes one revolution for the advance of each sheet. On this disk rests the arm P either directly 10 or by means of the roller T. In this manner it is possible to lift the arm P and also the arm A in the desired moment. This curved disk S can also be used to return the freeing device to its starting position when a projection U thereof engages behind a corresponding projection V of the freeing device 15 F. As the latter descends the locking device G with its nose I snaps into the recess thereof and holds the same in its depressed 20 position.

Usually for a sheet feeding arrangement two friction wheels and two freeing arrangements are requisite and the arrangement of the two must be made easily adjustable 25 corresponding to the width of sheet and so that the friction wheels can only travel over unprinted places of the sheet. For this reason according to the present invention all parts of the freeing device are mounted on a common cross carrier W. This also insures a 30 good mounting of the several parts and their effective engagement or mesh during

work. The freeing arrangement as an entirety can be first mounted and placed into the machine in complete condition, and is 35 therefore also dismountable as a whole. By the compact arrangement of the entire freeing arrangement it is also possible to operate on sheets of twenty-seven and one half (27½) 40 cm. width by this arrangement while the former arrangements of similar sort are able to deliver only sheets of at least 35 to 36 cm. The sheets are forwarded to the roll A by any suitable feeding machine (not shown) 45 and are taken from the roll L by the gripper of any printing press or the like.

What I claim is:—

Sheet feeding mechanism comprising a friction wheel, lever mechanism for setting the wheel into and out of action, a freeing device for actuating the lever mechanism to raise the wheel, a locking device for the freeing device, a sheet feeler for actuating the locking device, and tappet mechanism for moving the locking device to releasing position.

In testimony whereof I have hereunto set my hand in the presence of two subscribing witnesses.

GEORG SPIESS.
